UNITED STATES PATENT OFFICE.

HERMAN A. WEBER, OF HARTFORD, CONNECTICUT.

SPARK-ARRESTER AND SMOKE-TREATING DEVICE.

1,109,884.

Specification of Letters Patent.

Patented Sept. 8, 1914.

Application filed October 15, 1912. Serial No. 725,860.

To all whom it may concern:

Be it known that I, HERMAN A. WEBER, a citizen of the United States, residing at Hartford, in the county of Hartford and 5 State of Connecticut, have invented new and useful Improvements in Spark-Arresters and Smoke-Treating Devices, of which the following is a specification.

My invention relates to a combined spark 10 arrester and smoke treating device for use in connection with steam engines.

One object of my invention is to provide a device wherein live sparks are prevented from escaping to the atmosphere, the temperature of the products of combustion being materially reduced previous to its escape 15 to the atmosphere.

Another object of my invention is to provide means in a smoke chamber to drive 20 the smoke and cinders inwardly so that they will be treated and discharged adjacent the lower part of the chamber.

Other objects will hereinafter appear as the preferred embodiment of the invention 25 is described in connection with the accompanying drawings, wherein—

Figure 1 is an end view of the boiler of a steam engine showing the invention in connection therewith, and, Fig. 2 is a vertical 30 sectional view through the same parts.

Referring to the drawings, 1 designates that portion of the boiler of a steam engine into which the smoke passes for escape through a usual smoke stack. In place of 35 the usual smoke stack I have provided a stack or upper chamber 2 which is closed at its top and secured to the boiler portion 1 by bolts or rivets 3 or in any other suitable manner. Across the stack 2 extends a partition designated 4 which provides a passageway 5 for the escaping smoke and another passageway in which is secured a hopper or receptacle 6 provided with outlet 40 openings at opposite ends. The numeral 7 designates a cinder discharge chute which is provided with inlet openings on opposite sides thereof. The discharge chute 7 opens into the boiler part 1 and is secured thereto in any suitable manner. Arcuate channel 45 members 8 are secured exterior of the boiler part 1 as by means of bolts 9, which members 8 have their hollow portions at one end register with the openings of the chute 7, and which hollow members at their opposite 50 ends enter the stack 2 and have their openings register with the openings of the re-

ceptacle 6. In the discharge chute 7 is removably mounted a valve or slide designated 10 which has a projection extending through the wall of said chute, which is provided with a flange 12 to which is secured an operating handle 13. A revoluble fan member 14 is mounted on a frame 15 located in a side opening 16 of the stack 2. A smoke flue or duct consisting of a connection of pipes 17 leads from the stack 2 and is connected to a smoke treating chamber 18 in any suitable manner, which chamber is supported in any suitable manner preferably exterior of the boiler portion as upon the running-board 70 of the engine which is designated 17'. In said chamber are provided a number of staggered baffle plates 19 to provide a tortuous passage for the escaping smoke. An outlet pipe 20 is connected to the smoke treating chamber, thereby providing for the ultimate escape of the products of combustion, preferably at a point below and at one side of the boiler 1.

Above the receptacle 6 and adjacent the outlet opening for the pipe connection 17, is secured a suitable cinder deflector plate 21, as by means of bolts or rivets 22 passing through the upper wall of the chamber 2.

As the steam engine, to which my improvement is applied travels, the air acts against the fan 14 and revolves the same. The smoke passing through the boiler portion 1 will pass up through the passageway 5 and be driven toward the outlet opening 90 leading to the smoke flue. Large cinders that may be carried upward by the smoke will also be driven toward said outlet and will strike against the plate 21 and be deflected or fall into the receptacle 6, from whence they will pass through the passages of the channel members 8 and into the discharge chute 7, resting upon the slide 10. When a quantity of cinders have collected in the discharge chute and passages of the channel members, said slide may be withdrawn in order to discharge said cinders. The smaller cinders, live sparks, and smoke passing through the duct will be discharged into the smoke treating chamber 18 and will follow a tortuous or broken passage between the baffle plates thereof, being finally discharged to the atmosphere through the discharge pipe 20, the live sparks having by this time been subdued.

It is to be understood that I have described and illustrated herein the preferred

embodiment of my invention only, and that changes in the details of construction thereof may be made within the spirit and scope of the appended claims, and hence are 5 served by me.

Having thus described my said invention, what I claim and desire to secure by Letters Patent is—

1. In a spark arrester and smoke treating 10 device for locomotives, the combination of a discharge chamber for the products of combustion, a hopper disposed within said chamber, a cinder discharge chute, channels communicating the said hopper with the said 15 chute, means for directing the cinders into the hopper, of an air driven fan arranged adjacent an opening formed within the said chamber, the said opening being arranged to receive a direct current of air during the 20 forward travel of the locomotive, a chamber outlet pipe, a smoke treating chamber into which the said pipe discharges, a plurality of baffle plates arranged within the said chamber, and an outlet pipe connected to the 25 said chamber adapted to discharge the treated smoke to the atmosphere at a point adjacent the ground, as and for the purpose set forth.

2. In a spark arrester and smoke treating 30 device for locomotives, the combination of a discharge chamber for the products of combustion, a hopper disposed within said chamber, a cinder discharge chute, arcuate channels communicating the said hopper 35 with the said chute, an arcuate baffle plate disposed to direct the cinders into the hopper, and means carried by said chute for controlling the outlet thereof, of an air driven fan arranged adjacent an opening 40 formed within the said chamber, the said opening being disposed to receive a direct current of air during the forward travel of the locomotive, a pipe leading from the said chamber exteriorly of the locomotive and to 45 one side thereof, the said baffle being arranged adjacent the pipe opening, a smoke treating chamber into which the smoke is

conveyed, a plurality of spaced oppositely extending baffle plates arranged within the said chamber, and an outlet pipe connected to the opposite end of the said chamber from that of the said first mentioned pipe, the said outlet adapted to discharge the treated smoke to the atmosphere at a point adjacent the ground and at one side of the locomotive. 50 55

3. In a spark arrester and smoke treating device for locomotives, the combination of a smoke stack having a discharge chamber formed therein adapted to receive the products of combustion, a partition arranged within the said smoke stack, a hopper disposed within the said chamber, a cinder discharge chute, arcuate channels communicating the said hopper with the said chute, an arcuate baffle plate depending from the top of the said stack, the said plate being disposed to direct the cinders into the said hopper, and valve means carried by the said chute for controlling the outlet thereof, of an air driven fan arranged within an opening formed within the said stack and disposed to receive a direct current of air during the forward travel of the locomotive, the said air current adapted to direct the 70 product of combustion against the said arcuate baffle plate, a pipe leading from the said chamber at a point adjacent the said baffle, a smoke treating chamber arranged exteriorly of the locomotive into which the 80 said pipe extends, a plurality of uniformly spaced oppositely extending baffle plates arranged within the said smoke treating chamber, and an outlet pipe leading from the opposite end of the chamber from that to 85 which the said first mentioned pipe is secured for conveying the treated smoke to the atmosphere at a point adjacent the ground and at one side of the locomotive, as and for the purpose set forth.

HERMAN A. WEBER.
